ALICK L. CARTER, OF CLYDE, OHIO.

INTERNAL-COMBUSTION MOTOR.

1,116,994.

Specification of Letters Patent. Patented Nov. 10, 1914.

Application filed October 19, 1912. Serial No. 726,704.

To all whom it may concern:

Be it known that I, ALICK L. CARTER, a subject of the King of Great Britain, and a resident of Clyde, in the county of Sandusky and State of Ohio, have invented a new and Improved Internal-Combustion Motor, of which the following is a full, clear, and exact description.

My invention relates to an improvement 10 in internal combustion engines, and the object thereof is to provide a motor of the kind mentioned, preferably of the two-cycle type, which is designed to afford efficient and prompt and complete admission of the 15 fuel charge when the piston is about at the end of its cut stroke, together with a thorough cooling of all of the working parts of the engine when the same is in operation. These advantages I attain by the use of a 20 cylinder containing a reciprocating sleeve valve which surrounds the piston, the valve having a pumping attachment which fits in an enlargement of the cylinder bore adjacent the head thereof, this pumping attachment 25 serving to compress the fuel in a space formed by the inside surface of said bore, and a projection which extends inward from the head of the cylinder and enters the inner end of the sleeve, this sleeve also having 30 suitable ports which control the inflow and outflow of gas at the proper time with regard to the piston stroke.

On the drawings, the figure shows a side elevation partly broken away to show the 35 interior parts in section of an engine embodying my invention.

Referring particularly to the drawings I show an engine framework 1, which comprises a pair of cylinders 2 bolted or otherwise secured to a crank case 3. This engine is preferably of the two cycle type, though I do not necessarily limit my invention to this kind of motor, and neither do I limit myself to two cylinders, as shown, the number 45 of cylinders being immaterial. The upper ends of these cylinders are inclosed by a water jacket 4, to which leads a supply pipe 5, and inside of each of the cylinders reciprocates a piston 6 connected by a rod 7 50 to a crank 8 on a shaft 9 rotating in bearings in the crank case, and having at one end a flywheel 10. The jacket 4 surrounds the portion of each cylinder 2 which incloses

the firing chamber, and each cylinder has its bore enlarged at the head end to form a 55 space of increased diameter 11. Into this space extends a projection 12 carried by the head of each cylinder 2, and having its central axis forming a continuation of the axis of the cylinder itself. This projection 12, however, is not of the same diameter as the inside diameter of the firing chamber 60 inclosed by each cylinder 2, but its radius is less than the radius of the firing chamber by an amount equal to the thickness of a reciprocating sleeve 13, which fits into the normal bore of the cylinder and surrounds the piston 6, and is open at both ends, receiving at its inner end the inner end of the projection 12.

The space between the inner surface of the enlarged bore of the cylinder and the cylindrical outer surface of the projection 12 forms an annular chamber in which reciprocates a pumping piston secured to the 75 upper end of the sleeve 13. This pumping piston is preferably cast integral with the sleeve and comprises a shoulder 14 and a longitudinal extension 15 carried upon the upper end of the sleeve 13, and this sleeve 80 carries at its lower end a pair of bearings 16 which receive pins 18 engaging rods 17 which carry at their opposite ends suitable straps to engage eccentrics 19 on either side of the crank pin 8; and from this construction it will be seen that both the sleeve and piston are reciprocated when the shaft 9 rotates.

Adjacent the enlarged bore 11 and above the space 4 receiving the cooling fluid I 90 form an annular passage 20 in the wall of the cylinder which communicates with the space between the inner surface of the bore 11 and the surface of the extension 12 through circumferential openings 21. It 95 will also be seen that the sleeve 13 has openings 22 adjacent the collar 14, which establish communication between the inside of the sleeve 13 which forms the power chamber and the pumping space below the 100 pumping attachment. All the parts above described are alike in both cylinders, and the annular chambers 20 for each cylinder at the head ends thereof communicate with an intake pipe 23 which supplies them with 105 explosive mixture from the carbureter. The

sleeve 13 also has outlet openings 24 circumferentially arranged thereof to communicate with similar openings in the wall of the cylinder leading to an annular outlet chamber 25. This outlet chamber for each cylinder is connected to an exhaust header 26 to lead the burnt gases away from the engine.

The outlet for the water jacket of the engine is shown at 27, and it communicates by means of branch pipes, as shown at 28, with a cooling space 29 formed in the walls of the extensions 12. The cooling fluid thus passes not only through the jacket 4 around the firing chamber to the cylinders 2, but also passes into the extension 12 and keeps the head of the cylinder cool also. This arrangement prevents premature heating of the gases before they enter the firing chamber, and thus the danger of the gases exploding when compressed by the piston 6 before the ignition apparatus is energized is obviated.

It will be noted that the heads of the cylinders 2 have openings 30 leading to the space behind the pumping attachment on the sleeve 13. Air is pumped into the space behind the pumping piston through these holes on the intake and out stroke thereof, and free movement of the sleeve 13 is thus facilitated.

The bottom of the crank case 3 contains cups 31 which may be integral with the bottom plate and having openings in the bottom closed by plugs 32. The bearing at the end of the connecting rod shown at 32' is provided with lubricating passages, and to these passages leads a short section of piping 33 carried by the bearing end 32' of the connecting rod, this section of piping to be open at both ends and arranged to dip into the oil in the cup or pocket 31. Oil thus passes through this pipe and lubricates the crank pin 8. On the opposite side of the bearing 32' is an outlet opening 34 to which oil can pass to be splashed upon other parts of the motor. The projection 12 is hollow, as shown at 35, and has a central opening 36 which may be used to receive an igniter.

The operation of my invention is as follows: On the compression stroke the piston 6 will move toward the head of the cylinder to compress the charge in the firing chamber, and the sleeve 13 will also move toward the head of the cylinder at this time, the projection 12 closing the openings 22, and the openings 24 being taken out of registry with the openings leading to the exhaust chamber 25. Hence, a vacuum will be created between the collar or flange 14 and the shoulder of the enlarged bore 11, and as soon as the pumping attachment overruns the ports 21, mixture from the carburetor and chamber 20 will flow into the space between the side of the bore 11 and the ex-

tension 12. The mixture is now fired and the piston 6 moves outward. The sleeve 13 is now moved outward also, and the ports 21 covered and the charge in front of the collar 14 compressed. At the end of the firing stroke the ports 24 establish communication with the exhaust chamber 25 and the burnt gases flow out of the exhaust header 26. About the end of the exhausting operation the ports 22 overrun the end of the projection 12, and the highly compressed mixture in advance of the working face of the pumping attachment flows into the firing chamber of the cylinder 2 and drives the rest of the exhaust gas out through the exhaust passages 24. This operation is repeated for each cycle, and is the same for all the cylinders. The eccentrics are of course arranged on the shaft 9 so as to cause the sleeve 13 to move outward to open the ports 22 at the right point for the admission of the fuel mixture. These eccentrics may be adjustable if desired, and thus the exhausting is completed and the intake likewise effected. It is to be noted that the openings 22 and 24 extend all around the sleeve 13 and a complete clearing out of the working chamber results. By this arrangement the formation of a pocket of inert products of combustion near the top of the working chamber is made impossible.

The piston, the extension 12 and the extension 15 of the pumping attachment will of course be provided with suitable packing rings to prevent leakage. The water jacket will efficiently cool the walls of the cylinders adjacent the firing chambers, and the walls of the extension 12 as well, so that the gas entering the space between the projection 12 and the surface of the bore 11 will not be heated before being compressed to the point required at the time when it enters the working chamber through the openings 22. It is to be noted also that on the up stroke the pumping attachment carried by the sleeve creates a partial vacuum between the sleeve and the surface of the bore 11, so that as soon as the ports 21 are uncovered the charge rushes in. Furthermore, the ports 21 and the ports 22 and 24 are not uncovered until the sleeves and the piston are adjacent the end of the stroke, when the motion of these parts is slowest, and thus the outflow and inflow of gases have plenty of time to take place at high speeds.

It will be seen that there are two branches 28 leading in each projection 12. The pipe 27, as shown in the drawing may have a partition inside of the same between the members of each pair of branches 28, so as to cause the fluid to flow through the hollow walls of each projection before it passes on to the radiator.

While I apply the principle of my engine preferably to a two-cycle motor, I desire not

to be limited to this type, but wish to have it understood that the above description is illustrative only, disclosing but one embodiment of my invention, and I reserve to myself the right to make whatever changes in the shape, size and arrangement of the parts as fairly fall within the scope and spirit of my invention.

Having thus described my invention, I claim as new and desire to secure by Letters Patent:

1. In an internal combustion engine, the combination of a cylinder having the bore thereof enlarged at the head end, a reciprocating sleeve valve in said cylinder and forming a firing chamber, the cylinder having a projection extending into the head end and forming with the cylinder wall a fuel pumping chamber in said enlarged end of the cylinder, a piston in the firing chamber and moving in the said reciprocating sleeve valve, and a piston carried by the reciprocating sleeve valve and working in the pumping chamber, a fuel mixture chamber surrounding the pumping chamber and communicating by ports directly with the pumping chamber for the passage of the fuel mixture into the latter, the said ports being controlled directly by the piston in the pumping chamber, the sleeve valve being provided with ports below the said piston, the said ports being controlled by the said projection and adapted to overrun the end of the same to permit the charge to pass directly from the pumping chamber into the firing chamber, and means for operating said pistons at different speeds, the piston in the pumping chamber creating a vacuum therein before the fuel mixture is admitted thereto.

2. In an internal combustion engine, the combination of a cylinder having a reciprocating sleeve valve therein forming a working chamber, a piston reciprocating in the said working chamber, the cylinder having its bore enlarged at the head end and having an annular fuel supply chamber formed in its wall and surrounding the enlarged portion of the cylinder, a projection carried by the cylinder head and extending into the enlarged bore, an annular pumping piston carried by the reciprocating sleeve valve and moving in the space between the said projection and the inner surface of the enlarged portion of the cylinder, said space communicating directly with the fuel supply chamber through circumferential ports in the wall of the enlarged portion of the cylinder, and also adapted to communicate directly with the working chamber through circumferential ports in the said sleeve valve at its junction with the piston, means for operating the working piston, and means for operating the reciprocating sleeve valve to cause the pumping piston to draw fuel

into said space from the fuel chamber and compress the same and deliver fuel to the working chamber.

3. In an internal combustion engine, the combination of a cylinder having a reciprocating sleeve valve therein forming a working chamber, a piston in the said working chamber, a projection carried by the cylinder head and extending into the cylinder, the projection being spaced from the wall of the cylinder to form an annular fuel pumping chamber at said end of the cylinder, the wall of said chamber being provided with ports, an annular carbureter chamber surrounding the said pumping chamber, and communicating directly therewith through said ports, an annular piston carried by said sleeve valve and moving in the said pumping chamber and controlling said ports, the sleeve valve having ports extending therethrough below the said annular piston for establishing direct communication between the pumping chamber and the said working chamber.

4. In an internal combustion engine, the combination of a cylinder having a reciprocating sleeve valve therein forming a working chamber, a piston in the said working chamber, the bore of said cylinder being enlarged at its head end, a projection carried by the cylinder head and extending into the enlarged bore, the wall of said enlarged bore having ports therethrough, an annular carbureter chamber surrounding the enlarged portion of the cylinder and communicating directly therewith through said ports in the cylinder wall, an annular piston carried by the sleeve valve and moving in the space between the wall of the enlarged bore and the projection on the cylinder head—the said piston controlling said ports, means comprising ports extending through the sleeve valve adjacent its junction with the annular piston for establishing direct communication between said space, below the said annular piston, and the said working chamber, and means for operating said pistons.

5. In an internal combustion engine, the combination of a cylinder having an exhaust passage surrounding the same and exhaust ports leading to said passage, the said cylinder having the bore thereof enlarged at the head end, a fuel chamber surrounding the enlarged bore, an annular pumping chamber formed in the enlarged end of the cylinder the wall of the cylinder forming the outer wall of said pumping chamber and having ports therethrough opening directly into the fuel chamber, a reciprocating sleeve valve in said cylinder and forming a working chamber, an annular pumping piston carried by said sleeve valve and moving in said pumping chamber, the said piston controlling the ports communicating

4
with the fuel chamber, the said sleeve valve having ports extending therethrough adjacent its junction with the annular piston, the said ports being adapted to overrun the end of the inner wall of the pumping chamber to establish direct communication between the pumping chamber and the working chamber, the said sleeve valve also having ports adapted to register with the exhaust ports of the cylinder, a piston mov-

ing in the said working chamber, and means for operating the working piston and the reciprocating sleeve valve.

In testimony whereof I have signed my name to this specification in the presence of 15 two subscribing witnesses.
